(57) **CLAIM**

The ornamental design for a fuel filter for vehicle, as shown and described.

DESCRIPTION

FIG. 1 is a perspective view from a front, plan, and right side of a fuel filter for vehicle showing our new design;
FIG. 2 is a perspective view from rear, plan, and left side thereof;

FIG. 3 is a front view thereof;

FIG. 4 is a rear view thereof;

FIG. 5 is a plan view thereof;

FIG. 6 is a bottom view thereof;

FIG. 7 is a right side view thereof;

FIG. 8 is a left side view thereof;

FIG. 9 is an enlarged cross-sectional view thereof taken along line 9-9 in FIG. 3;

FIG. 10 is an enlarged cross-sectional view thereof taken along line 10-10 in FIG. 5;

FIG. 11 is a perspective view from a front, plan, and right side of another fuel filter for vehicle showing our new design;

FIG. 12 is a perspective view from rear, plan, and left side thereof;

FIG. 13 is a front view thereof;

FIG. 14 is a rear view thereof;

FIG. 15 is a plan view thereof;

FIG. 16 is a bottom view thereof;

FIG. 17 is a right side view thereof; and,

FIG. 18 is a left side view thereof.

The broken lines depict portions of the fuel filter for vehicle that form no part of claimed design.
